(57) **CLAIM**

The ornamental design for a modular wall panel with integral form work, as shown and described.

DESCRIPTION

FIG. 1 is a front perspective view of a modular wall panel with integral form work in accordance with my design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof; and,

FIG. 8 is an enlarged fragmentary section taken along line 8-8 of FIG. 4.
The dash-dot-dot-dash broken lines in FIG. 8 depict the limits of the enlarged fragmentary view.

1 Claim, 4 Drawing Sheets
